UNITED STATES PATENT OFFICE.

LOUIS DAVIS, OF RICH HILL, MISSOURI, ASSIGNOR OF ONE-HALF TO I. L. WIERICK, OF RICH HILL, MISSOURI.

IGNITION SYSTEM FOR HYDROCARBON-ENGINES.

1,177,496.

Specification of Letters Patent.

Patented Mar. 28, 1916.

Application filed April 26, 1915. Serial No. 24,002.

To all whom it may concern:

Be it known that I, LOUIS DAVIS, a citizen of the United States of America, residing at Rich Hill, in the county of Bates and State 5 of Missouri, have invented new and useful Improvements in Ignition Systems for Hydrocarbon-Engines, of which the following is a specification.

This invention relates to improvements in 10 ignition systems for hydrocarbon engines and has particular application to the timer structure.

In carrying out the present invention, it 15 is my purpose to provide a timer for the ignition systems of hydrocarbon engines which will be constructed in such manner that the wiring of the system may be simplified and a single vibrator or induction coil employed to take care of all of the spark 20 plugs.

With the above and other objects in view, the invention consists in the construction, combination and arrangement of parts hereinafter set forth in and falling within the 25 scope of the claims.

In the accompanying drawing; the figure is a diagrammatic view of an ignition system equipped with a timer constructed in accordance with the present invention.

Referring now to the drawing in detail, 30 1 designates a suitable source of electrical energy, such, for instance, as a battery, 2 indicates an induction coil and 3 designates my improved timer, while the spark plugs 35 in the cylinders of the engine are indicated at 4.

My improved timer comprises an outer ring 4 preferably composed of insulating material, an inner ring 5 disposed concentrically of the outer ring and preferably formed of conducting material and a contact arm 6 pivoted at the center of the inner ring 5. Secured to the inner edge of the ring 4 and spaced apart equidistant are contacts 9, while secured to the inner edge of the ring 5 are contacts 10 spaced apart equidistant and corresponding to the contacts 9 respectively. Rotatably mounted upon the arm 6 are rollers 7 and 8 designed to engage 45 the contacts 10 and 9 respectively in the rotation of the arm 6. As usual, the arm 6 is connected with the timer shaft of the engine and is driven from such shaft.

Leading from one side of the battery 1 is 50 a conductor 11 connected to one terminal of

the primary winding of the vibrator coil 2 and leading from the remaining terminal of the primary winding of the vibrator coil is a conductor 12 terminally connected with the arm 6. One side of the secondary winding of the induction coil is connected to the conductor 12 by way of a wire 13, while the remaining terminal of the secondary winding is grounded as at 14. From the contacts 9 in the ring 4 lead conductors 15 connected with the power electrodes of the respective spark plugs 4, while the remaining electrodes of the spark plugs are grounded upon the engine as usual. A switch 16 is preferably located in the conductor 11 so that the ignition circuit may be made and broken whenever desired.

In practice, when the switch 16 is closed, current flows from one side of the battery 1, through the conductor 11, the primary winding of the coil 2, the conductor 12, the contact arm 6, the roller 7, the contact 10 in engagement with such roller, the ring 5 and back to the other side of the battery by way of a conductor 17 that connects the ring 5 with the battery. When the primary winding is thus energized the vibrator is set in action and as a result a high potential current is produced in the secondary winding and flows through the wire 13, the portion 55 of the conductor 12, the arm 6, contact roller 8, the contact 9, in engagement with the roller 8, the spark plugs of the engine and back to the other side of the secondary winding of the induction coil by way of the ground. Thus, a spark is created at the electrodes of the spark plugs to ignite the charge in the engine cylinders. In the operation 60 of the engine, the arm 6 is revolved and the rollers 7 and 8 engage the contacts 10 and 9 respectively successively, thereby energizing the spark plugs in the respective engine cylinders in the proper order.

I claim:

In an ignition system for hydrocarbon engines, a source of electrical energy, an induction coil, a timer comprising an inner conducting ring, contacts on the inner edge of said ring and spaced apart equidistant, an outer ring disposed concentrically of the inner ring, contacts on the inner edge of the outer ring spaced apart equidistant and corresponding to the first-mentioned contacts, a contact arm pivoted to the center of said inner ring and capable of rotation, 100

rollers carried by said arm and adapted to engage the contacts on said inner and outer rings respectively successively in the rotation of said arm, a connection between one terminal of the battery and one terminal of the primary winding of said induction coil, a connection between the remaining terminal of the primary winding of the induction coil and said arm, a connection between said 10 conducting ring and the other side of said battery, a connection between the secondary winding of said coil and the connection be-

tween the primary winding and said arm, the remaining terminal of the secondary winding being grounded, and connections 15 between the contacts in said outer ring and the power electrodes of the respective spark plugs.

In testimony whereof I affix my signature in presence of two witnesses.

LOUIS DAVIS.
